UNITED STATES PATENT OFFICE.

ALEXANDER CAMPBELL, OF HALIFAX, ENGLAND

INTERNAL-COMBUSTION ENGINE.

No. 872,497.

Specification of Letters Patent.

Patented Dec. 3, 1907.

Application filed November 13, 1906. Serial No. 343,195.

To all whom it may concern:

Be it known that I, ALEXANDER CAMPBELL, residing at 7 Dunkirk Crescent, Halifax, Yorkshire, England, have invented certain new and useful Improvements in Internal-Combustion Engines; and I do hereby declare the following to be a full, clear, and exact description of the invention, such as will enable others skilled in the art to which it appertains to make and use the same.

This invention relates to internal combustion engines, and consists in producing an electric spark within the cylinder, to ignite the combustible mixture therein at the required time, by means of a circuit breaking plunger actuated by the engine piston.

In the drawings, Figure 1 is a longitudinal section through the rear end of a gas-engine cylinder provided with an igniter according to this invention. Fig. 2 is a similar longitudinal section showing a modification in the igniter.

The invention will be clearly understood by reference to the annexed drawings forming a part of this specification.

Referring firstly to Figure 1, *a* represents in section a portion of the combustion end of the cylinder, into which is screwed or otherwise fitted a circular plug *b*, bolted or fixed by any other convenient means on to the outside wall of the water jacket *c*, and made of any size and shape to suit the engine to which it is applied. Within the plug, and insulated therefrom at the points *d*, is a conductor tube *e*, into which is fixed a terminal *f* connected to one pole of a magneto, dynamo, accumulator or other suitable source of electric current. Within this tube *e*, and insulated therefrom at the points *g*, is a flanged tube or socket *h* through which works freely a plunger comprising a second flanged tube or sleeve *i* and a spindle *j* screwed through the said tube *i*. The spring *k* normally holds down the plunger so that the flange on the end of the sleeve *i* is in contact with the contact-plate or cap *l* attached by the screwed ferrule *m* to the conductor tube *e*, and the terminal *n* on the spring case *n* is wired to the body of the engine, which is in connection at any convenient point with the other pole of the dynamo or the like, so that the current passes through the cap *l* and sleeve *i*. When the piston *o* returns to the combustion end of the cylinder it presses in the projecting end of the spindle *j*, thereby separating the flanged sleeve *i* from the con-

tact-plate or cap *l*, when an electric spark or series of sparks passes between these parts, which ignites the combustible mixture. To regulate the time at which the spark occurs, the spindle *j* can be screwed up or down within its sleeve *i*, reducing or increasing its projection beyond the cap *l*, so that the piston will strike the said spindle later or sooner as may be desired. A pinion *j'* (which may be actuated by a gear wheel operated, in the case of a motor road vehicle, from the dashboard) is provided on the spindle *j*, so that such alteration can conveniently be effected while the engine is at work.

The nut or washer *p* which may be made in two parts clamped together upon the upper end of the sleeve *i* is shown with a projection or lug *p'* thereon fitting into a slot *n'* in the spring case *n*. This allows the nut or washer *p* to rise and fall with the plunger but prevents the sleeve *i* from rotating with the spindle *j*.

If it is not necessary to provide means for varying the time at which the spark occurs, that is if it is requisite that the spark should always occur at a fixed point in the working cycle of the engine, the flanged tube or sleeve *i* and the spindle *j* may be made integral or in one piece and the gear wheels will not then be required.

Referring now to Fig. 2 which illustrates a modification, the conductor tube *e* is dispensed with, the plate *l* being screwed or attached directly to the plug *b* and being in contact with the engine, to which the wire carrying current from one pole is led, the other wire being led to the spring case *n* as before mentioned. The piston must then be insulated at *g* to allow of the circuit being broken by the movement of the plunger.

The igniters may be placed either parallel with the walls of the cylinder as shown or at an angle thereto, as may be required by the design of the engine.

My invention, although perhaps especially applicable to the engines or motors of motor road vehicles, can be applied to internal combustion engines in general.

I claim as my invention:

1. The combination, with a supporting plug, of a contact-plate secured to the said plug, a tube or socket carried by the said plug and insulated from the said contact-plate, a contact-sleeve slidable in the said tube or socket and provided with means for preventing it from revolving, a spring which

normally holds the said contact-sleeve and contact-plate in contact, and a longitudinally-adjustable spindle screwthreaded to engage with the said contact-sleeve and projecting past the said contact-plate.

2. The combination, with a supporting plug, of an insulated conductor-tube carried by the said plug, a contact-plate carried by the said conductor-tube and also insulated from the said plug, a tube or socket secured inside the said conductor-tube and insulated from it, a contact-sleeve slidable in the said tube or socket and provided with means for

15 preventing it from revolving, a spring which normally holds the said contact-sleeve and contact-plate in contact, and a longitudinally-adjustable spindle screwthreaded to engage with the said contact-sleeve and projecting past the said contact-plate.

20 In testimony whereof I affix my signature, in presence of two witnesses.

ALEXANDER CAMPBELL.
